UNITED STATES PATENT OFFICE.

ALEXANDER McGARY, OF LAGRANGE, ILLINOIS.

AUTOMATIC ELECTRIC REGULATOR.

SPECIFICATION forming part of Letters Patent No. 776,144, dated November 29, 1904.

Application filed April 20, 1903. Serial No. 153,499. (No model.)

To all whom it may concern:

Be it known that I, ALEXANDER McGARY, a citizen of the United States, residing at La-
5 grange, in the county of Cook and State of Illinois, have invented certain new and useful
Improvements in Automatic Electric Regu-
lators, of which the following is a specification.

This invention relates to means for regulat-
ing the electromotive force or current upon
10 circuits that are supplied with electricity from
sources or other circuits wherein the poten-
tial, current, or electromotive force is subject
to great variation, as instanced in car-axle
lighting systems, in street-car headlight and
15 interior lamp-circuits, in storage-battery
charging-circuits depending on central or mu-
nicipal circuits, and the like; and the invention
has special reference to automatic regu-
lators for electric circuits, which include stor-
20 age batteries and electric lamps—arc or in-
candescent. Numerous and ingenious con-
trivances have been invented for controlling
or governing the presence and introduction of
resistance in such circuits for the purpose of
25 maintaining a constant current or electromo-
tive force upon the supplied circuit. Each
of these devices, as I am informed, is charac-
terized by a row or series of resistance ter-
minals or contacts and a collector, sweep, or
30 contact finger or arm, which is automatically
actuated by mechanical means under magnetic
control. Many have been complicated by
the use of small electric motors which supply
the mechanical force needed for the operation
35 of the resistance-varying sweep or arm.
Electric controllers or regulators that are built
upon such lines of necessity include a large
number of mechanical elements or parts and
an equally-extended group of magnetic parts,
40 all of which are frail and weak and which
taken together constitute an electromagnetic
mechanism of such complexity of functions
and structures as to court failure and inac-
curacy in operation. Furthermore, the parts
45 of these complicated many-movement regu-
lators frequently bind and refuse to per-
form their work because of the excessive
temperature to which they are subjected by
the highly-heated resistance-coils that are

always placed in close proximity to the work- 50
ing parts of such regulators. Experience
has demonstrated the unreliability of present-
day controllers or regulators as a class, that
they are difficult to keep in order, and are the
most frequent sources of trouble in the bat- 55
tery and lamp circuits wherein they are used.

The object of my invention is to improve
the operation of electric regulators and to
greatly simplify the construction thereof and
render their action more certain and reliable. 60

Another object of my invention is to pro-
vide an electric controller or regulator that
shall admit of the subdivision of the resist-
ance to any extent desired or required by the
service to be performed by the translating de- 65
vices in circuit.

I conceive that the chief difficulties encoun-
tered in the present controllers or regulators
arise from and are attendant upon the em-
ployment of a rigid collector-brush or sweep 70
in combination with rigid resistance-sections
or contacts. These elements make it neces-
sary to employ complex auto-driven mechan-
ical elements that are short-lived, the efficiency
of which varies with surrounding conditions, 75
which are comparatively slow in operation,
and which offer a varying frictional and me-
chanical opposition to quick, accurate move-
ment in place of the uniform forces and con-
ditions which the problem demands. Pro- 80
ceeding on this conception I have determined
upon the elimination of the usual rigid or
solid metal sweep or collector, as well as all
of the mechanical and auxiliary electrical and
electromagnetic elements and members found 85
in other regulators, and in place thereof I
have adopted a liquid current-collector for co-
operation with the necessary resistance-coil
terminals or contacts with a very simple and
reliable electromagnetic device for actuating 90
and controlling the movement of what I have
thus termed the "liquid current-collector."

My invention, broadly considered, consists
in a liquid container or receptacle having,
preferably in its walls, the requisite number 95
of resistance terminals or contacts, suitably
insulated, and arranged at different points or
elevations, in combination with a fluid, liq-

uid, or plastic substance, preferably mercury, in said receptacle, and a liquid-displacing device that is electromagnetically operated or controlled and which by its movement 5 causes the liquid to rise or fall into contact with higher or lower terminals, as the case may be, said liquid being included in the electric circuit and having a suitable terminal in either said container or said displacing device 10 or plunger, and, further, my invention consists in various constructions and combinations of parts and in circuit arrangements, all as hereinafter described, and particularly pointed out in the claims.

15 The invention will be more readily understood by reference to the accompanying drawings, forming a part of this specification, in which—

Figure 1 is a vertical section of an automatic electric regulator embodying my invention. Fig. 2 is a similar view showing the displacing device or plunger in its lowest position. Fig. 3 is a horizontal section on the line $\alpha\alpha$ of Fig. 1, and Fig. 4 is a diagrammatic view showing the circuits of the regulator.

As shown in the drawings, 2 represents a solenoid, supported by brackets 3, which extend from the backboard or slab 4.

30 5 is the measuring-pot or liquid-container supported upon but insulated from the bracket 6. The pot 5 is preferably arranged beneath the solenoid 2 and contains the central guide or standard 27.

35 7 is the solenoid-core, having on its lower end a tubular extension 8 to slide upon the standard 27. The extension 8 carries the displacing device or plunger 9, which is preferably a hollow cup of less diameter than the 40 pot or container 5, a narrow annular space 10 being left between the plunger 9 and the inner walls of the pot 5.

The parts 5 and 9 may be of any desired cross-section or shape, and any convenient 45 means other than the standard or post 27 may be used for guiding the plunger and the solenoid-core.

11 11 11 11 are the resistance-terminals. These are placed close together in an inclined or 50 spiral row, stepping upward from the bottom of the pot to the top thereof. The pot-walls thus accommodate a very large number of resistance-coil terminals within a very small space measured vertically, and it is obvious 55 that this construction enables me to use as many terminals as may be required for nice regulation by the fine subdivision of the resistance. The difference between the elevations of adjacent terminals or contacts may be as 60 slight or as great as differing conditions require, yet with entire freedom from the usual difficulties pertaining to contact areas and insulation. The terminals may be of any desired design or pattern; but I preferably em-

ploy simple screws 12, that pierce the insulating-plugs 13, which fill the holes 14 in the walls of the pot, the ends of the screws being bare within the pot or container. The screws have washers 15 of insulating material.

16 16 represent the wires or connections 70 leading to the resistance-coils.

The pot 5 is partially filled with a liquid 17, preferably mercury, which is a good conductor, and when the plunger falls or is depressed it displaces the mercury and drives it upward 75 between the plunger and the walls of the pot or container, forcing the mercury into contact with the exposed or contact ends of the resistance-terminals. When the plunger is raised, the column of mercury falls and is thus withdrawn from contact with one or all of the terminals, according to the height to which the plunger is lifted.

18 and 19 are the main terminals of the solenoid, and 20 20 are the taps that are connected 85 to the several upper coils or sections of the solenoid.

Referring now to Fig. 3, it will be seen that current enters over the main-circuit line 21, which is connected to the end or first terminal 90 of the resistance 22. The lower end of the resistance is connected by the wire 14' to the lowest terminal or contact 11 on the regulator-pot. From this terminal or from any point on the metal pot 5 a line 23 leads to the upper connection 18 of the solenoid. From thence the circuit is traced through the windings of the solenoid to the outgoing or working branch 24 of the supplied circuit. As shown, the resistance-terminal connections 14 100 connect respective terminals upon the pot and the coils or sections of the resistance 22. The highest terminal 11 is connected to the end of the resistance and line 21. As shown in Figs. 1 and 2, the cup-plunger 9 is loaded or weighted with a quantity of mercury 25, placed therein, and I may also employ a coiled spring within the post 27 to assist in depressing the plunger. I prefer in most cases to weight 110 the plunger with mercury and to dispense with the spring; but either or both means may be used.

At times when the solenoid is deenergized the plunger will be in its lowest position, as shown in Fig. 2, and the column of mercury will be elevated, as therein shown, 115 so that it will be in electrical contact with all of the resistance-terminals 11. Thus at the instant when the circuit is energized the current will pass immediately from the line 21 to the mercury in the pot and from thence to the bottom terminal and to the solenoid, the resistance at that instant being all cut out. The solenoid will therefore be instantly and powerfully energized and acting upon the solenoid-core will lift the plunger 9 and allow 120 the mercury in the pot to fall. When the plunger is lifted, it is obvious that a number 125 of the upper terminals upon the pot will be

uncovered and left bare by the fall of the liquid, thereby interrupting the direct passage of the current from the line 21 to the body of mercury and forcing the current to traverse a number of coils or sections of the resistance 22 before reaching a coil having a terminal that is still covered by the mercury. From such a covered terminal the current finally reaches the mercury and finds a direct passage to the line 23, the remaining resistance being effectively cut out by the first direct mercury connection supplemented by the many avenues of escape afforded by the connections 14 of the lower terminals. A very strong current in the solenoid will produce a complete elevation of the plunger and by allowing the mercury to fall below all of the terminals will put all of the resistance into the circuit. The elevation to which the plunger will be raised and at which it will be held will depend upon the strength of the current in the solenoid, and this in turn is controlled by the quantity of effective resistance in the circuit. The device operates almost instantaneously with every fluctuation of the current or electromotive force upon the circuit wherein it is used, compensating therefor and resulting in a constant current, potential, or electromotive force, as the case may be, on the working branch 24 of the main circuit.

It will be noted that the greatest displacement of the mercury in the pot occurs at the time when there is the least resistance in circuit and that the solenoid has less weight to raise at the beginning of the stroke of the core than after it is partially elevated. The force of the solenoid, however, increases as the core enters it and its increased effectiveness is usually sufficient to compensate for the increased weight of the plunger when lifted. I, however, prefer to arbitrarily increase the strength of the solenoid as the plunger is lifted and to this end employ auxiliary solenoid-windings 2', formed by tapping the coils of the solenoid at different heights. The taps 20 lead to auxiliary terminals 20', provided in the wall of the pot and at different elevations. The lowest tap 20 leads to the uppermost terminal 20' and the upper tap leads to the lower terminal 20'. The result of these connections is that when the mercury is elevated in the pot the upper coils of the solenoid will be practically short-circuited or weakened by being thrown into multiple arrangement, while upon the elevation of the plunger and when the solenoid needs assistance the terminals 20', one or all, will be bared by the fall of the mercury, thereby restoring the corresponding coils to active series circuit in the solenoid to further compensate for the increased weight that must be lifted and sustained by the solenoid.

It is obvious that numerous modifications of my invention will readily suggest them-

selves to one skilled in the art, and I therefore do not confine my invention to the specific constructions, circuits, and arrangements herein shown and described. 65

Having thus described my invention, I claim as new and desire to secure by Letters Patent— 70

1. In an automatic electric regulator a solenoid having a core, in combination with a cup-plunger directly coupled to and forming mechanically a part of said core, and concentric therewith, a liquid-pot containing said plunger, and a conducting fluid in said pot, substantially as described. 75

2. In an automatic electric regulator a solenoid provided with a plurality of taps, a liquid-pot, a series of auxiliary contact-points 80 insulated in the walls of said pot and connected with said taps, a conducting fluid within said pot, and means for displacing said liquid within said pot, substantially as and for the purposes described. 85

3. In an automatic electric regulator, a liquid-pot provided with a spirally-arranged series of insulated contacts in its walls, auxiliary contacts at different elevations in said pot, a solenoid having taps connected with said auxiliary contacts, a conducting fluid in said pot, said solenoid operating to raise or depress the level of said liquid within said pot, substantially as and for the purpose specified. 90

4. An automatic electric regulator, comprising a solenoid having a core, a pot containing a conducting liquid, a plunger directly coupled to said core and operable in said pot, and an inclined series of independent resistance-terminals insulated in the walls of said pot, substantially as described. 95

5. In an automatic electric regulator, a solenoid provided with taps, a core in said solenoid, a liquid-cup, a plunger in said cup and coupled to and forming mechanically a part of 105 said solenoid-core, a series of independently-insulated resistance-terminals spirally placed at varying heights in the walls of said cup, independently-insulated auxiliary terminals in the walls of said cup connected with said solenoid-taps, and a conducting liquid in said cup, substantially as described. 110

6. An automatic electric regulator, comprising a pot, in combination, with a plurality of stepped resistance-terminals insulated on the 115 walls of said pot and arranged spirally thereon, a suitably-guided plunger for operation in said pot, a solenoid and a solenoid-core coupled to and concentric with said plunger, substantially as described. 120

7. An automatic electric regulator, comprising a pot or container, a conducting liquid therein, a plunger, the solenoid having its core concentric with and forming mechanically a part of said plunger, a resistance, a plurality of resistance-coil terminals, having contacts within said pot and insulated from one another, and a circuit branch electrically con- 125

nected with said conducting liquid and includ-
ing said solenoid, substantially as described.

8. The automatic electric regulator, comprising a pot or vessel, in combination, with
5 the resistance-terminals arranged at different elevations in said pot, a body of mercury in
said pot, a cup-plunger operable directly by
electromagnetic means and reversible by
gravity in said pot, and a load of mercury in
10 said plunger, substantially as described.

9. An automatic electric regulator, comprising a liquid pot or container, in combination, with a plurality of resistance-terminals having exposed contacts at different elevations in
15 said pot, a conducting liquid provided in said pot, a plunger for displacing said liquid, the
spring operating upon said plunger to depress
the same and an electromagnetic device for
20 withdrawing said plunger, substantially as de-
scribed.

10. An automatic electric regulator, comprising the liquid-container, in combination, with a plurality of resistance-terminals of vary-
ing elevation, the conducting liquid in said
25 pot, the displacing-plunger, the solenoid hav-
ing a core coupled to said plunger, the auxil-
iary terminals in said pot and the solenoid-
taps connected with said auxiliary terminals,
substantially as described.

11. An automatic electric regulator, com-
prising a metallic liquid-pot, in combination
with a plurality of resistance-terminals hav-
ing exposed contacts at different elevations
in said pot and independently insulated in the
30 walls thereof, a conducting liquid in said pot,
a plunger for displacing said liquid, depressible
by gravity, and an electromagnetic device
35 for raising said plunger, substantially as de-
scribed.

12. In an automatic electric regulator, in
combination, a pot, a conducting liquid in said
pot, a plunger in said pot, depressible by
gravity, for raising the level of said liquid, a
solenoid for raising said plunger and thereby
40 depressing the level of said liquid, a resistance
in circuit with said solenoid, and a plurality
of spirally-arranged resistance-terminals hav-
ing bare contacts, exposed to said liquid in
said pot, substantially as described.

In testimony whereof I have hereunto set
my hand, this 14th day of April, 1903, at Chi-
cago, Illinois, in the presence of two wit-
nesses.

ALEXANDER McGARY.
